OHIO

COOLING SYSTEM FOR INTERNAL-COMBUSTION ENGINES

Application filed March 16, 1928. Serial No. 262,068.

This invention relates in general to aeronautics, and is more particularly concerned with cooling systems of internal combustion engines for airplanes or other aircraft having aerofoil surfaces.

The invention has for its object the provision of a steam cooling system for such engines, so constructed and arranged as to provide efficient cooling of the engine under all conditions of service, and which accomplishes this result without the manifest disadvantages inherent in the use of water cooling systems.

Another object of our invention is to so arrange our vapor condenser that it will serve to tend to prevent the formation of ice thereon while the craft is passing through snow and sleet and at the same time provide a condenser perfectly streamlined with the aircraft.

With these objects in view, this invention consists of the novel construction of the cooling system, in the steam or vapor condenser, and in the connections and parts.

It is a further, and most important object of our invention to provide a steam cooling means in which the condenser and its component parts are arranged without any additional head resistance to the aircraft and one which presents the minimum of vulnerability to hostile aircraft or ground fire.

The invention further consists of certain arrangements and combinations of parts, all of which will be first fully described and afterwards specifically pointed out in the appended claims.

Referring to the accompanying drawing:

Figure 1 is a view partly in side elevation and partly in vertical section illustrating the cooling system in operative position, and,

Figure 2 is a fragmentary view of an airplane wing partly in section and illustrating the steam or vapor condenser in the wing of a pursuit airplane.

Figure 3 is a detail in section showing a portion of our condensing chamber.

Like numerals of references indicate the same parts throughout the figures, in which:

1 indicates an internal combustion engine partly in section to illustrate the cylinders 2.

3 is a manifold over the cylinder heads and

connecting with the water jackets 4. The manifold 3 includes a nipple or other suitable end 5 to receive the tube or pipe 6, flexible or otherwise, and an enlarged downwardly depending portion 7 formed to reenter the water jacket 4 at the extreme bottom thereof.

Applied to this depending portion 7 in the usual manner is a gage glass 8 having two prominent calibrations 9 thereon, between which the level of the water in the motor 1 and manifold should be maintained for most efficient operation of the system.

10 indicates the wing 1 or other aerofoil of an airplane, within the interior of which we position an elongated steam or vapor receiving tank 11 to which the tube or pipe 6 is connected as by means of a nipple 12 terminating at 13 above the bottom of the tank 11, as shown in the drawing. From the bottom of the said tank 11 at the front and rear thereof, 70 we provide suitable drain pipes 14 and 15 which may merge at 16, into a single pipe 17 and connect to the bottom of the depending portion 7 of the manifold 3.

The whole or a suitable portion of the interior of the wing or aerofoil 10 may be employed as a condensing chamber 18, the size and extent of this chamber depending on size and type of the aircraft and its power plant.

Projecting laterally from each side of the receiving tank 11 and near the top thereof are a plurality of condensing pipes 19, the length of which pipes is coincident with the length of the condensing chamber 18, as will appear from Figure 2. The said pipes 19 are provided along their upper surfaces with a series of perforations 20 through which the steam or vapor passes into the condensing chamber 18.

Under some conditions, we may find it advisable to supply over each row of perforations, considered longitudinally of the craft, an up-raised corrugation in the surface 21 to receive and deflect the steam or vapor as it passes into the condensing chamber 18. In some installations this may not be necessary. In fact it is to be understood that the construction and arrangement of the parts of the entire system may be changed or altered with the scope of the invention in order to meet

conditions and requirements as they are found to exist.

Positioned preferably below the chassis of the airplane or otherwise conveniently placed is an air driven circulating pump 22 connected to a small vented drain tank 23, within a stream-lined shell 24. In some cases this drain tank will be incorporated in an airfoil surface or other streamlined portion of the 10 aircraft landing gear.

Connecting the condensing chamber 18 with the drain tank 23 are one or more drain pipes 25 leading from the drain ports 30, see Figure 2, while the pump 22 is piped to the 15 bottom of the depending portion 7 in order to deliver to the engine water jacket the contents of the said drain tank 23 as it passes thereto from the condensing chamber 18.

Connected also to the said depending portion 20 of the manifold 3 by a pipe 26 is a water supply tank 27, the contents of which are supplied to the engine water jacket by a conduit 28, controlled by a manually controlled valve 28a, in order to maintain the 25 proper level within the same as indicated by the gage 8.

Having thus fully described the invention, its operation will be seen to be as follows:

Water being supplied to the water jacket 30 of the engine to the desired level as indicated by the gage glass 28, the steam and vapor therefrom is delivered to the receiving tank 11 in the wing or aerofoil 10. Such water as accompanies the steam and vapor is separated either by the action of the deflector 30' into the manifold portion 7 or is carried into the receiving tank 11 and there separated. Such water as reaches the tank 11 is immediately returned, together with the 35 condensate of the steam condensed in said tank, to the engine water jacket through the drain pipes 14 and 15. The uncondensed steam passing from the receiving tank 11 into the projecting condensing pipes 19 is now quite dry. The substantially dry steam and 40 vapor passes from the condensing pipes 19 through the perforations 20 and into the condensing chamber 18 where the final condensation takes place and the condensate therefrom passes through the drains 25, preferably 45 led along and streamlined with the adjacent struts, to the drain tank 23 whence it is returned to the engine water jacket 4 by the circulating pump 22. At 50 we have disclosed an additional circulating pump for forcing the cooling water through the cylinder jackets at a comparatively high velocity. This provision eliminates the necessity of large 55 capacity water jackets and increases the efficiency of our heat transfer system. This pump may be dispensed with, if desired in some types of engines.

Having thus fully described the invention we do not wish to be understood as limiting 60 ourselves to the exact construction herein set

forth as the same is susceptible to various changes in the construction and arrangement of the component parts of the system without departing from the spirit of the invention, and we consider ourselves clearly entitled to all such changes and modifications as fall within the limit and scope of the appended claims.

We claim:

1. A device of the character described including, in combination with the water jacket of an internal combustion engine, a manifold above the water jacket, said manifold including a depending portion for connection with the water jacket at the bottom thereof, a steam and vapor receiving tank disposed internally of an airplane wing or aerofoil of an aircraft, means for connecting the manifold with the receiving tank to deliver into the receiving tank the steam and vapor from the water jacket, a series of perforated condensing pipes projecting from each side of the receiving tank into a condensing chamber within the wing or airfoil, longitudinally extending corrugations over the perforations in the condensing pipes, a vented drain tank, means connecting the condensing chamber with the drain tank to drain the condensate from the condensing chamber, a wind driven circulating pump for returning the contents of the drain tank to the engine water jacket, means for draining the condensate of the receiving tank into the water jacket, a supply tank communicating with the water jacket, means for delivering the contents of the supply tank to the water jacket, and a gage-glass on the depending portion of the manifold for indicating the water level within the depending manifold.

2. A device of the character described including, in combination with the water jacket of an internal combustion engine, a manifold above the water jacket, said manifold including an enlarged depending portion for connection with the water jacket at the bottom thereof, a steam and vapor receiving tank disposed internally of an airplane wing or aerofoil of an aircraft, means for connecting the manifold with the receiving tank, a series of perforated condensing pipes projecting from the receiving tank into a condensing chamber within the wing or aerofoil, a drain tank, means connecting the condensing chamber with the drain tank, a circulating pump for returning the contents of the drain tank to the engine water jacket, means for draining the condensate of the receiving tank into the water jacket, a supply tank communicating with the water jacket, and means for delivering the contents of the supply tank to the water jacket.

3. A device of the character described including, in combination with the water jacket of an internal combustion engine, a manifold above the water jacket, said manifold in-

the drain tank to the engine water jacket, means for draining the condensate of the receiving tank into the engine water jacket, a supply tank for the engine water jacket, and means for indicating the water level in the depending manifold portion.

10. A device of the character described including, in combination with the water jacket of an internal combustion engine, a manifold above the water jacket, said manifold including a depending portion for connection with the water jacket at the bottom thereof, a circulating pump for circulating water through said jacket and said manifold, a steam and vapor receiving tank disposed internally of an airplane wing or aerofoil of an aircraft, means for connecting the manifold with the receiving tank, steam condensing means connected to the receiving tank to deliver steam and vapor therefrom into a condensing chamber within the wing or aerofoil, a drain tank connected to the condensing chamber, a circulating pump for returning the contents of the drain tank to the engine water jacket, means for draining the condensate of the receiving tank into the engine water jacket, a supply tank for the engine water jacket, and means for indicating the water level in the depending manifold portion.
20. 11. A device of the character described including, in combination with the water jacket of an internal combustion engine, a manifold above the water jacket, said manifold including a depending portion for connection with the water jacket at the bottom thereof, a baffle for deflecting such water as may accompany the steam and vapor in the manifold into said depending portion, a steam and vapor receiving tank disposed internally of an airplane wing or aerofoil of an aircraft, means for connecting the manifold with the receiving tank, steam condensing means connected to the receiving tank to deliver steam and vapor therefrom into a condensing chamber within the wing or aerofoil, a drain tank connected to the condensing chamber, a circulating pump for returning the contents of the drain tank to the engine water jacket, means for draining the condensate of the receiving tank into the engine water jacket, a supply tank for the engine water jacket, means for indicating the water level in the depending manifold portion and an additional circulating pump arranged between the depending portion of the manifold and the water jacket.

12. A device of the character described including, in combination with the water jacket of an internal combustion engine, a manifold above the water jacket, said manifold including a depending portion for connection with the water jacket at the bottom thereof, a steam and vapor receiving tank disposed internally of an airplane wing or aerofoil of an aircraft, means for connecting the manifold with the

receiving tank, steam condensing means connected to the receiving tank to deliver steam and vapor therefrom into a condensing chamber within the wing or aerofoil, a drain tank connected to the condensing chamber, a circulating pump for returning the contents of the drain tank to the engine water jacket, means for draining the condensate of the receiving tank into the engine water jacket, a supply tank for the engine water jacket, a hand controlled valve for controlling admission of water from said supply tank to said water jacket, and means for indicating the water level in the depending manifold portion.

In testimony whereof we affix our signatures.
